UNITED STATES PATENT OFFICE.

HARRY S. UBER, OF PHILADELPHIA, PENNSYLVANIA.

TUBE HOLDER.

Application filed January 6, 1922. Serial No. 527,505.

To all whom it may concern:

Be it known that I, HARRY S. UBER, a citizen of the United States, residing at Philadelphia, in the county of Philadelphia and State of Pennsylvania, have invented 5 certain new and useful Improvements in a Tube Holder, of which the following is a specification.

My invention relates to improvements in 10 a tube holder, and particularly to a holder for collapsible tubes containing tooth paste, shaving cream, glue, paint and the like.

The object of my invention is to construct 15 a tube holder which is adapted to receive tubes of various sizes, and which may be readily inserted and removed from the holder; a further object is to provide a tube holder comprising a base and a carriage movably mounted thereon, having novel 20 features of construction and arrangement of the parts which increase the usefulness of the device, simplify its operation, and reduce the cost of manufacture; a further object is to provide a spring for retarding the 25 movement of the carriage, which is moved by the winding of the collapsible end of the tube upon a shaft, whereby the tube will be tightly wound upon said shaft and thus completely discharge the contents of the 30 tube, and a still further object of my invention is to provide a handle upon the device which is capable of having two separate movements, one for turning a shaft for compressing the tube and the other movement for opening and closing a valve 35 controlling the discharge end of the tube.

Referring to the drawing:—Fig. 1, is a front elevation of my improved tube holder showing the valve in the open position; Fig. 40 2, is a side elevation of the tube holder; Fig. 3, is a vertical section of the tube holder showing the valve closed; Fig. 4, is a plan view of Fig. 1, Fig. 5 is an inverted plan view of Fig. 1; Fig. 6 is a plan view of the 45 tube holder with the parts shown in the position to close the valve; and Fig. 7, is an inverted plan view of the tube holder showing the valve in the closed position.

In the accompanying drawing, in which 50 like reference characters refer to like parts, 1 represents base which is of channel formation, having a plane surface or back 2, adapted to be secured upon a vertical wall. The base 1 has off-set flanges 3 and 4 forming parallel sides which form tracks for the 55 carriage 6.

Secured to the lower end of the base 1 is a bracket 7 having an aperture 8 formed through the same for the insertion of the discharge end or nozzle 9 of the tube 10. 60 Said aperture 8 is made large in diameter so as to receive the largest size tube which may be used upon the holder. The end or nozzle 9 of the tube is secured in the bracket 7 by a thumb-screw 12 mounted in a 65 threaded aperture formed in the bracket 7.

The carriage 6 consists of two side plates 14 and 15 having inwardly turned edges 16 which project under the flanges 3 and 4 of the base 1. Said side plates 14 and 15 are 70 held together in spaced relation to each other by a cross-piece 18, secured to said plates. Secured upon the cross piece 18 is a plate spring 20, the ends of which press against the base 1, thus holding the carriage 75 from sliding upon the base by the action of its own weight during the time a new tube is being placed in the holder or the empty tube is being removed.

A shaft 22 is rotatably mounted in the 80 side plates 14 and 15 of the carriage. The shaft 22 is provided with a longitudinal slot 23 formed through the same for the reception of the flat end of the tube 10, which is to be wound around the shaft. The ends 85 of the shaft 22 project beyond the plates 14 and 15. The shaft 22 is held against longitudinal movement by a fastening device, such as a pin 25 located at one end of the shaft, and by a shoulder 26 formed by the 90 enlarged square portion 28 upon the opposite end of the shaft 22.

A handle 30, in the form of a wheel, is 95 slidably mounted upon the square portion 28 of the shaft 22. By turning the handle the shaft will be rotated and the tube may be wound thereon for compressing the latter. A valve 35 is provided for closing the discharge end of nozzle 9 of the tube. The valve 35 is in the form of a spring plate 100 which is mounted below the under side of the bracket 7, and is adapted to press tightly against the bracket and cover the aperture 8 formed through the bracket. The valve plate 35 is secured, at its rear end, to 105 the lower end of a rod 36, which latter is rotatably mounted in the bracket 7 and in an angle plate 38, extending from the top of the base 1. By turning the rod 36 the valve plate 35 may be moved into the position shown in Figs. 1, 4 and 5, so as to 110 open the said aperture 8 formed in the

bracket 7, and also open the end or nozzle 9 of the tube which latter may be secured in the bracket 7 so that the lower end surface of the nozzle 9 will be flush with the valve plate 35 and the latter will thus form an air tight closure for the tube, when the valve 35 is in the closed position as shown in Figs. 2, 3, 6 and 7.

The valve 35 may be opened and closed by 10 a sliding movement of the handle 30 upon the square end 28 of the shaft 22. The handle 30 is provided with a flange 40, which forms an annular groove into which extends the turned end 41 of a sliding plate 42, slid- 15 ably mounted in the side plates 14 and 15 of the carriage 6. The sliding plate 42 is provided with a wider portion between the side plates of the carriage which forms shoulder 44 and 45, adapted to take against 20 said side plates 14 and 15 and thus limit the movement of the sliding plate 42 and also prevent the handle 30 from coming off the shaft 28.

The sliding plate 42 is provided with a 25 portion forming a lug 46 extending at right angles to the main part of the sliding plate. Said lug 46 provides a bearing for the link 48, which is pivotally attached to the lug 46, by the pin or rivet 49. The link 48 is pro- 30 vided with a rectangular aperture 50 formed through the same and through which aperture extends the rod 36, also of rectangular formation throughout the length of travel of the carriage 6 upon the base 1. The link 48 35 slides freely upon the square rod 36 and the link will act as a crank arm and turn the rod when the sliding plate 42 is moved by sliding the handle 30 upon the shaft 22 and the rod 36 will actuate the valve 35.

40 The operation of my invention is as follows: The base is secured in a fixed position upon a suitable support; the carriage is slid upon the base to a position at the upper end of the base where it is held by the action of 45 the spring 20; a tube, having the screw cap removed is now placed upon the bracket so that the nozzle will extend through the aperture formed in the bracket and its end surface will rest upon the valve plate 35, in which 50 position the tube is secured in the bracket by the thumb screw 12; the carriage is now moved downwardly until the flat end of the tube will enter the slot formed in the shaft 22; by turning the handle 30 the shaft will 55 cause the tube to be wound around it; as the tube shortens the carriage will be drawn towards the fixed bracket 7 and the spring on the carriage will press against the base and retard the movement of the carriage 60 sufficiently to insure the tube being tightly wound upon the shaft and thus discharge all the contents of the tube, thus eliminating any waste of material. The discharge end of the tube is conveniently opened and closed 65 by simply sliding the handle 30 upon the

shaft which will operate the valve through the medium of the rod pivotally mounted upon the base and carrying the valve.

Having thus described my invention I claim and desire to secure by Letters Pa- 70 tent:—

1. A tube holding device comprising, a base, a part secured to the base for holding one end of a collapsible tube, a part movable upon the base for holding the opposite end 75 of said tube, mechanism for compressing the tube and discharging the contents thereof, a valve for controlling the discharge opening of the tube, and a handle operatively mounted upon the device for controlling the movement of the said mechanism for compressing the tube and for controlling the movement of the said valve.

2. A tube holding device comprising, a base, a part secured to the base for holding one end of a collapsible tube, a part movable upon the base for holding the opposite end 85 of said tube, mechanism for compressing the tube and discharging the contents thereof, a valve for controlling the discharge opening of the tube, and a handle operatively 90 mounted upon the device and capable of two separate movements, one of said movements for actuating the said mechanism for compressing the tube and the other movement 95 for actuating the said valve.

3. A tube holding device comprising; a base, a part secured to the base for holding one end of a collapsible tube, a part movable upon the base for holding the opposite end 100 of said tube, mechanism for compressing the tube and discharging the contents thereof, a valve for controlling the discharge opening of the tube, a handle operatively mounted upon the device whereby a rectilinear 105 movement of the handle opens and closes the valve and a rotary movement of the handle operates the said mechanism for compressing the tube.

4. A tube holder comprising a base, a 110 part secured to the base for holding one end of a tube, a part movable upon said base, a shaft rotatably mounted in the said movable part, said shaft adapted to engage and wind one end of a collapsible tube thereon, a han- 115 dle, upon the shaft for rotating the shaft, said handle being slidably mounted upon the shaft, a valve for opening and closing the discharge end of said tube, and actuating means connecting the valve with the handle 120 whereby a sliding movement of the handle upon the shaft will actuate the valve.

5. A tube holder comprising a base, a part secured to the base for holding one end of a tube, a part movable upon said base, a shaft rotatably mounted in the said movable part, said shaft adapted to engage and wind one 125 end of a collapsible tube thereon, a handle upon the shaft for rotating the shaft, said handle being slidably mounted upon the 130

shaft, a valve for opening and closing the discharge end of said tube, a rod rotatably mounted upon the base and adapted to actuate the valve and mechanism operatively mounted between the rod and the handle whereby a sliding movement of the handle upon said shaft will rotate the rod and actuate the valve.

6. A tube holder comprising a base, a part secured to the base for holding one end of a tube, a part movable upon said base, a shaft rotatably mounted in the said movable part, said shaft adapted to engage and wind one end of a collapsible tube thereon, a handle upon the shaft for rotating the shaft, said handle being slidably mounted upon the shaft, a valve for opening and closing the discharge end of said tube, a rod rotatably mounted upon the base and adapted to actuate the valve, a member slidably mounted upon the rod adapted to reciprocate the latter and mechanism operatively mounted between the said member and the handle whereby a sliding movement of the handle upon said shaft will operate the rod and the valve.

7. A tube holder comprising a base, a part secured to the base for holding one end of a tube, a part movable upon said base, a shaft rotatably mounted in the said movable part, said shaft adapted to engage and wind one end of a collapsible tube thereon, a handle upon the shaft for rotating the shaft, said handle being slidably mounted upon the shaft, a valve for opening and closing the discharge end of said tube, a plate slidably mounted in the part carrying the said shaft, said plate and said handle being in operative engagement whereby a sliding movement of the handle upon the shaft will move the plate, a link pivotally connected with the said plate, a rod rotatably mounted upon the base and adapted to actuate the valve and said link slidably mounted upon said rod and secured against rotation upon the latter.

8. A tube holder comprising a base, a part secured to the base for holding one end of a tube, a part movable upon said base, a shaft rotatably mounted in the said movable part, said shaft adapted to engage and wind one end of a collapsible tube thereon, a handle upon the shaft for rotating the shaft, said

handle being slidably mounted upon the shaft, a valve for opening and closing the discharge end of said tube, a plate slidably mounted in the part carrying the said shaft, said plate and said handle being in operative engagement whereby a sliding movement of the handle upon the shaft will move the plate, a square rod rotatably mounted in the base and extending at right angles to the plane of the movement of the plate, a link pivotally attached to the said plate and having a square aperture formed therein through which the square rod freely passes and is adapted to be rotated by the link and a valve actuated by the said rod.

9. A tube holder comprising a base, a part secured to the base for holding one end of a tube, a part movable upon said base, a shaft rotatably mounted in the said movable part, said shaft adapted to engage and wind one end of a collapsible tube thereon, a handle upon the shaft for rotating the shaft, said handle being slidably mounted upon the shaft, a valve for opening and closing the discharge end of said tube, a plate slidably mounted in the part carrying the said shaft, said plate and said handle being in operative engagement whereby a sliding movement of the handle upon the shaft will move the plate, a stop formed upon said plate to limit the movement of the handle upon the shaft, a valve for opening and closing the discharge end of the tube and mechanism operatively connecting the said plate with the valve.

10. A tube holder comprising a base, a carriage slidably mounted upon the base, a spring upon the carriage to retard the movement of the carriage, a bracket upon the base for securing the discharge end of a collapsible tube, a shaft rotatably mounted in the carriage and adapted to have the tube wound around the same, a handle for rotating the shaft, a valve for closing the discharge end of the tube, a rod for operating the valve, a link for turning the rod to operate the valve, said link mounted upon the carriage and slidably upon the rod, and connecting mechanism between the link and the handle for operating the valve by the handle.

In testimony whereof I affix my signature.
HARRY S. UBER.
